LINKING MACHINE

Application filed June 6, 1928, Serial No. 283,316, and in France June 18, 1927.

The invention has for its object the application of the rotary loop-forming hook, to which is imparted a uniform rotary movement, to linking machines or knitted fabric sewing machines used in hosiery.

This rotary hook can be fitted to any linking machine or knitted fabric sewing machine, circular or parallel, and with the use of a curved needle or of a rectilinear needle.

It is known that linking machines exist in which the hook effects an oscillating movement in various planes. The necessary devices for imparting to the hook its movement comprise cams and springs; they can work only at a reduced speed owing to the mechanical inertia of the returning springs.

The machine forming the subject-matter of the invention presents, over the above-mentioned machines, the advantage that the cams and springs are entirely done away with for actuating the hook; this allows of operating at a higher speed with, moreover, a small consumption of energy (35 watts-hour) supplied by a motor of very small power (1/70 of H. P.). These economies directly result from the rational mechanical arrangement obtained by means of the invention.

Moreover, in the form of construction which will be described hereinafter by way of example, use is made of a rectilinear needle engaging with the leaf-needles by their heel piece (and not by their points).

With my invention the needle is guided perfectly in the rectilinear channels formed by the leaf-needles of the usual circular comb. Also the meshes are taken up throughout the length of the leaf-needle.

These mechanisms allow, on the one hand, to work knitting of great thickness and, on the other hand, they have the advantage of avoiding the cuttings (which unavoidably occur when the needle engages with the point of the leaf-needles).

The placing in position and adjustment of the needle is very easily effected.

The machine is adjusted once for all when it is fitted up; the rotary hook can be easily replaced on the spot.

The machine is illustrated in the accompanying drawing in which:

Fig. 1 is a side elevation of the linking machine in accordance with the invention.

Fig. 2 is a top plan view thereof.

Fig. 3 is a partial vertical section parallel to the needle bar or needle-carrier.

Fig. 4 is a diagrammatic plan view showing the relative arrangement of the needle passing through the circular comb and of the rotary hook.

Fig. 5 is a vertical section showing the parts imparting a reciprocating movement to the needle carrier.

Fig. 6 shows separately the rotary hook.

The drawing shows that the improved machine in accordance with the invention is of the circular type and comprises a number of elements which are known in this type of machines, viz:

A frame 1 forms a base and is surmounted by an arm 2 carrying a shaft 3 to the end of which is suspended and can rotate the rotary crown 4. The latter carries at its periphery a comb 5 and it receives a rotary movement, at short intervals, from a pawl 6, the nose of which pushes the teeth of a ratchet wheel 7 provided on the crown 4.

A main driving shaft 8 is actuated by a grooved pulley 9 actuated in its turn, through a belt 10, by the shaft 11 of a small electric motor 12.

It will be understood that the shaft 8 might be actuated by hand. It drives, as is well known, an eccentric strap 13 moving a rod 14, pivoted at 15, which rod, for each revolution of the shaft, causes the crown 4 to move to the extent of one tooth of the ratchet wheel; this displacement corresponds to the end of the execution of a stitch. A roller 16 comes under the comb 5 and holds, against the latter, the article of hosiery to be circularly stitched up.

The shaft 8 also drives the needle 17 and the rotary hook 18.

The latter is integral and co-axial with the shaft 8 at the end of which it is secured by any suitable means: key, screw, pin or the like.

The rectilinear needle 17 is secured on the long branch of an inverted vertical yoke 19 rigid with the needle-carrier 20.

This needle comes in engagement with the leaf-needles at their inner part, called heel-piece, this avoiding the risks of breakage or of warping of the teeth, which are frequent in the other machines in which the needle comes in engagement with the points of the leaf-needles.

The figures of the accompanying drawing illustrate, by way of example, the preferred form of construction of a mechanism ensuring the automatic and rational association of the rectilinear reciprocating movement of the needle with the continuous rotation of the hook.

At the end of the shaft 8 is mounted a second eccentric strap 21 driving a rod 22 on the end of which is pivoted a crank 23; the latter transmits to an intermediate shaft 24, on which it is keyed, the angular reciprocating movement it receives from the rod 22. The shaft 24, parallel to the shaft 8, is supported by bearings 25 and drives in its reciprocating movement of rotation a crank pin 26 terminated by a double fork 28; the opening 27 of the latter gives passage to the needle-carrier 20 sliding in a member 29 secured to the frame. The branches 28 coming in engagement with two rollers 30 integral with a U-shaped member 31 secured on the needle-carrier, impart to the latter, and consequently to the yoke 19 and to the needle 17, a rectilinear reciprocating movement.

The movement effected by the various parts, needle and hook, for forming the chain stitch will be described hereinafter.

The needle, provided with its thread, enters the groove of the leaf-needle, passes through the meshes of the knitted fabric and presents its thread to the hook, then slightly moves back for allowing the point of the hook to enter between the body of the needle and the thread.

The hook grips, by means of its "point," the thread presented by the needle; it pulls it through the preceding loop and effects half a revolution by progressively enlarging the loop thus formed.

The point of the hook abandons the loop to the heel piece of the hook; this heel piece, which is of suitable shape, grips one of the sides of the loop and turns it over for allowing it to completely free itself from the hook at the end of the operation; the heel piece causes the loop to slide on the back portion of the point of the hook which in its turn progressively abandons it, while the needle presents again its thread and allows it to be taken by the point of the hook which has come back to its first position; the needle withdraws for pulling the thread of the first loop forming and tightening the stitch.

The hook completely abandons the loop only at the time its point has already gripped the new thread for the next loop; at this

moment, it effects a complete revolution and is ready for the next stitch.

It is not necessary to describe with greater detail the operation of such a machine.

A machine thus constituted allows very smooth movements and a rigorously continuous action to be obtained, owing to the absence of any springs and cams. The hook is easily interchangeable, this considerably simplifying the adjustment of the machine and the conditions of use of the latter.

It is to be understood that the forms, constructional details, accessories, materials and dimensions of the improved machine may be varied without departing thereby from the scope of the invention.

Claims:-

1. A knitted fabric sewing machine, comprising a frame, a crown supported by this frame, a main driving shaft which continuously rotates, a comb on the periphery of this crown, a ratchet wheel fixed to the crown, an eccentric strap on the said main shaft, a rod rigid with this eccentric strap, a pawl actuated by the said rod and acting on the ratchet wheel, a rotary loop-forming hook rigid with the said main shaft and co-axial with the same, a secondary shaft receiving from the main shaft an angular reciprocating movement, a crank arm rigid with the secondary shaft, a needle-carrier terminated by a yoke and receiving the movement of the said crank arm, a needle secured on one of the branches of this yoke and radially moving relatively to the crown.

2. A knitted fabric sewing machine, comprising a frame, a crown supported by this frame, a main driving shaft which continuously rotates, a comb on the periphery of this crown, a ratchet wheel fixed to the crown, an eccentric strap on the said main shaft, a rod rigid with this eccentric strap, a pawl actuated by the said rod and acting on the ratchet wheel, a rotary loop-forming hook rigid with the said main shaft and co-axial with the same, a secondary shaft receiving from the main shaft an angular reciprocating movement, a crank arm rigid with the secondary shaft, a fork at the end of this crank arm, a needle-carrier terminated by a yoke, rollers on the carrier and extending in the fork of the crank arm, a needle secured on one of the branches of the said yoke and radially and alternately moving relatively to the crown.

The foregoing specification of my "linking machine" signed by me this 23rd day of May, 1928.

JEAN BAPTISTE VALTON.
